(Cl. D58—26)

To all whom it may concern:

Be it known that we, Harry W. Olson and Oscar A. Olsen, citizens of the United States, residing in Chicago, Cook County, State of Illinois, have invented a new, original, and ornamental Design for a Measuring Dispenser for Fine Solids, of which the following is a specification, reference being had to the accompanying drawing, forming a part thereof.

Figure 1 is a side elevational view of a measuring dispenser for fine solids, showing our new design;

Figure 2 is a front elevational view of the device as shown in Figure 1;

Figure 3 is a rear view; and

Figure 4 is a top plan view.

The dominant features of our design reside in the portions shown in full lines.

We claim:

The ornamental design for a measuring dispenser for fine solids, substantially as shown and described.

HARRY W. OLSON.
OSCAR A. OLSEN.
